UNITED STATES PATENT OFFICE.

HARRY H. WIGGLESWORTH AND WILLIAM P. GREINER, OF PHILADELPHIA, PENNSYLVANIA, ASSIGNORS TO THE PHILADELPHIA DRYING MACHINERY COMPANY, OF PHILADELPHIA, PENNSYLVANIA, A CORPORATION OF PENNSYLVANIA.

DRYING MACHINE.

Application filed April 18, 1924. Serial No. 707,346.

This invention relates to drying machines, and it has more particular reference to machines for drying knitted articles such as hosiery, for example, which are placed upon forms adapted to progress through an enclosure supplied with a drying medium, whereby evaporation of moisture from the articles is thoroughly effected, with incidental shaping of said articles before being stripped from the forms.

Hitherto, various types and combinations of instrumentalities have been employed for concurrently drying and shaping knitted fabrics with more or less successful results, but all have been comparatively expensive both in construction as well as operation. The primary object of our invention accordingly is to provide a novel form of machine of the typified character which is labor saving and economical in use, successful for the purpose had in view, and simple to construct or install.

Another object of this invention is to provide a drying machine for knit fabrics, the forms whereof are intermittently progressed through the drying enclosure per se with capacity for egress and ingress at juxtaposed stations, whereby an exposed form may be "stripped", concurrent with the "boarding" of another form.

A further object inhering to this invention is the provision of a drying machine through which an admixture of fresh air and drying medium circulates with a constantly-changing diffused-directional flow, so as to act upon the fabric articles from all angles during progression through the drying enclosure, per se.

With the foregoing and other objects in view, as later on noted,—or which will be apparent from the following description—our invention consists in the novel features of construction, combinations and arrangements of parts hereinafter fully described, illustrated by the accompanying drawings, and particularly featured in the appended claims. It is, however, to be clearly understood that various changes in the form, proportions, size and minor details of construction, may be made within the scope of the claims, without departing from the spirit, or sacrificing any of the advantages, of our said invention.

In order that this invention may be fully

understood and carried into effect, we will now describe the same with reference to the accompanying sheets of drawings, in which like characters indicate the same or corresponding parts in all the views.

Fig. I, is a sectional view through a knitted fabric drying machine conveniently embodying this invention, and as more specifically designed for drying hosiery.

Fig. II, is a vertical section taken substantially on the line II—II in the preceding figure.

Fig. III, is an enlarged fragmentary detail of the means for swinging the forms into "boarding" and "stripping" position.

Fig. IV, is a further enlarged and sectional view, taken approximately on the line IV—IV in the preceding figure.

Fig. V, is a fragmentary sectional view of a slightly modified embodiment of our invention; and,

Fig. VI, is a sectional view of a further modified form of this invention.

Referring first to the form of our invention illustrated by Figs. I—IV, more particularly, it will be seen that the drier comprises an enclosure comprehensively designated by the numeral 7, conveniently built of structural shapes or angles 8—8, and thermo-insulated sheet metal side panels 9, 9, a back wall 10, and frontal convergent panels 11, 11 affording a vertical interruption or opening 12, for a purpose later on to be explained. Thermo-insulated plates 13, 14 afford a roof and bottom, respectively, for the enclosure 7, and it is noteworthy that the shapes or angles 8—8 are downwardly extended at 8', so that said enclosure is located in spaced relation above ground or floor level. The downward or leg extensions 8'—8' are conveniently braced by transverse angle-section ties 15 to ensure rigidity and stability, as well as to accommodate certain instrumentalities hereinafter further referred to.

The enclosure 7 is sub-divided by a vertical partition 16 in spaced relation to the back wall 10, outwardly diverging opposed partitions 17, 17, and spaced parallel partitions 18, 18, thereby affording side passages 19, 19 functional as flow passages for the circulation of a drying medium, in addition to housing banks of heating coils 20, 20 located preferably as shown in the back

corners of said enclosure. Referring more particularly to Figs. I and II it will be noted that the parallel partitions 18, 18 terminate some distance away from the convergent panels 11, 11, and that the enclosure 7 is also provided with a front vertical partition 21 extending downward from the roof 14 into abutment with a stationary bearing bracket 22, and to which it is conveniently secured through the medium of bolts or rivets—not shown—secured to an upstanding flange 23 thereon. This frontal partition 21 is provided with diverging side wings 24, 25 functional as deflectors, a radially directed vertical partition 26, and a baffle 27 in parallel relation thereto, the purpose of each of which will be hereafter explained.

Intermediate the top and bottom of the back wall 10 and vertical partition 16, we construct a conduit 28, which is concentric with a walled opening 29 in said partition 16, within which revolves a fan 30, secured on a shaft 31, journalled in spaced bearings 32, mounted in said conduit 28. This shaft 31 projects exterior of the conduit 28 to afford connection for a belt pulley 33, which may be constantly driven from any convenient source of power. Cross-braces or angles 34 afford stable and rigid supports for the bearings 32.

The means employed for progressing the article-carrying forms or boards 35 through the drying enclosure 7 comprise a planetary disc or spider 36 revolvable about a stationary vertical axis 37, secured by a cotter pin 38—or the like—in a footstep bearing 39 supported on cross beams or angle sections 40, 40, in turn rigidly connected intermediate opposed pairs of the hereinbefore referred to transverse braces or ties 15, 15. As best seen from Figs. I and II, it will be observed, that the bearing bracket 22 is rigidly fixed by a cotter pin 41 to, and is supported by, the vertical axis 37 while the disc or spider 36 is freely revolvable thereon through the medium of a somewhat elongated boss or hub 42, afforded bearing on the top of the footstep 39. Obviously an appropriate anti-friction means—not shown—may be interposed between the lower end of the boss or hub 42 and the upper end of the footstep 39, to minimize friction thereat, if deemed necessary.

Mounted around the periphery of the disc or spider 36, or on lateral lugs 43—Fig. IV—integral therewith, and at equal distance apart, are a series of headed vertical studs 44 conveniently secured thereto by lock nuts 45, 46 as will be readily understood by those in any way conversant with the art. Freely pivoted by an elongated hub 47 to each vertical stud 44 is an upwardly inclined outrigger arm 48 of T—or angle—cross section, fashioned at its outer end to afford a seat 49 which is adapted to have an article-carrying

board 35 removably attached thereto, as by set screws 50. The boards 35 may be attached to a seat that is pivotally connected to the extremity of the arms 48, so that "boarded" hose can be examined on either side with facility. It is to be here noted that each article-carrying board 35 is disposed at a slight inclination over from the vertical; preferably—though not essentially—at an angle of ten degrees, to aid the operative in "boarding" the wet article thereon.

Integral with each hub 47—as best shown in Fig. III—are a series of laterally projecting upper lugs or fingers 51, 52, 53 and 54; and a pair of lower teeth 55, 56, it being noteworthy that the respective series are in parallel planes, while the purpose and function of each individual finger or tooth will be hereafter fully explained.

The means for rotating the planetary disc 35 or spider 36 to effect progression of the article-carrying boards 35 intermittently through the enclosure 7, comprises a toothed wheel 57 rigidly secured at the lower end of the hereinbefore referred to hub 42. This toothed wheel 57 is adapted for intermittent—or step by step—movement by means of a vertical pin 58 on a horizontally rotatable worm wheel 59 journalled to a suitable bearing 60 securely mounted on one of the transverse ties 15. This worm wheel 59 meshes with a worm 61 on a transverse shaft 62 journalled in bearings 63, and adapted to be driven at different speeds, through the instrumentality of a stepped pulley 64, from any convenient source of power—not shown.

To prevent back motion of the planetary disc or spider 36 and to hold the same in proper position while "stripping" and "boarding", we make use of a gravity-fall dog or pawl 65 adapted to engage the toothed wheel 57 and hold same stationary during the intervals when the vertical pin 58 is disengaged therefrom. It will, of course, be readily understood that the dog or pawl 65 is conveniently pivoted to a lug 66 secured to the enclosure bottom 14, and that said dog or pawl may be arranged in the path of—and raised by—the pin 58 in accordance with conventional practice, where such devices are employed.

In order to effect egress and ingress of the article-carrying boards 35, from and into, the drying enclosure 7, as well as affording means for maintaining the same relatively stationary during progression therethrough, we employ an annular ring 67 (Fig. I) of angle cross-section to afford a transverse flange 68 whereby it is attached to the bottom 14 of the drying enclosure 7; and a vertical flange 69, functional as a guide rail, and so designated hereafter. As best appreciated from Figs. I and II, this annular ring 67 is mounted concentric with the planetary disc or spider 36, with the teeth 55, 56 on

the outrigger arms 48 normally engaging the guide rail 69, except as hereafter explained. It is also to be observed, that the annular ring 67 does not completely surround the disc or spider 36, but that it is segmentally interrupted between the points 70, 71 for the insertion of a complementally curved cam sector 72.

Referring more particularly to Figs. I, III and IV, it will be seen that the cam sector 72 while conforming generally to the curvature of the annular ring 67, is fashioned to afford an upset bumper 73, having an obstruction or lateral projection 74 integral therewith, and a series of insets 75, 76 and 77. In spaced relation with the cam sector 72 it will be seen, we provide the hereinbefore referred to bearing bracket 22 with a vertical flange 78—Fig. III—affording a succession of cam-paths 79, 80 and 81 in radially increasing stepped relation. The aforesaid lateral projection 74, in conjunction with the cam-paths 79, 80 and 81, are successively effective to swing each outrigger arm 48, about its pivot stud 44, to present the attached article-carrying board 35, exteriorly of the drying enclosure 7, for “stripping” and “re-boarding” with a fresh article to be dried, as well as returning said board into the drying enclosure 7.

Assuming the drying machine is—as illustrated—adapted for drying hosiery, and that the planetary disc or spider 36, rotates in a counter-clockwise direction, it will be best understood from Figs. I and III, that as said disc or spider is progressed with an intermittent motion—hereinbefore set forth—all of the article-carrying boards 35 will be passed through the drying enclosure 7, in relatively stationary relation, by virtue of the teeth 55, 56; integral with each outrigger hub 47, engaging and being moved step-by-step over the inner face of the guide rail 69, as will be readily comprehended by those conversant with the art. The normal, or so termed relatively stationary, position of the article-carrying boards 35, is not to be misconstrued, as indicating said boards are immovable, such definition having been adopted to emphasize the fact that they do not turn with respect to each other during progression through the drying enclosure 7. In other words, each board 35 as it enters the drying enclosure 7, is moved into a plane obliquely tangential to the axis of rotation of the disc or spider 36, and retains such position—due to the instrumentalities aforesaid—during its entire progression therethrough. Such position, both as regards the board 35 as well as its associated turning means, is designated on the drawings by the letter *a*. When an article-carrying board 35 approaches the vertical egress opening 82—Fig. I—the lug or finger 51, on the associated outrigger-arm hub 47 will firstly

encounter the end 83 of the upset bumper 73, and swing the arm 48 about its pivot stud 44 with a clockwise motion from the position designated *a* to the dot-and-dash line intermediate position *a* shown in Fig. III, 70 whereupon the lug or finger 54 strikes the lateral projection 74 and thereby completes transfer of the article-carrying board 35 from enclosure progressing disposition to the position designated *b* where the “stripper” 75 operation is performed. At this juncture it is well to particularly note, that the two distinctive movements just described coincide with, or take place during, each progressive movement of the planetary disc 80 or spider 36, as will be well understood on an examination of Fig. III more particularly.

The following intermittent movement of the planetary disc or spider 36—brought about by the pin 58 engaging a succeeding tooth in the wheel 57—the outrigger arm 48 will be laterally swung from the stripper station *b* to that designated *c* through impact of the finger 52 with the forward end 90 of the vertical flange 78 on the bearing bracket 22, and partial cooperation with the cam path 79 in a counter-clockwise manner—as clearly appreciable from Fig. III. The succeeding intermittent movement of the planetary disc or spider 36 swings the stripped board 35 to the position designated *d* consequent upon the finger 52 completing traverse of the cam-path 79 and partial counter-clockwise movement over the cam-path 80, as best understood from Figs. I and III, where it is again clothed with a wet article by the operative—in the well-known way. The following intermittent movement of the planetary disc or spider 36 transfers the reclothed board 35 to the position marked *e*, as a result of the lug or finger 53 striking and moving on to the cam-path 81 with a further counter-clockwise action. At this point, attention is directed to the fact that the sequence of operative movements just described have resulted in independent motions being imparted to the outrigger arm 48, concurrent with each successive progressive part rotation of the planetary disc or spider 36. Consequently, the article-carrying board 35 has been swung out of the drying enclosure 7 through the egress opening 82, and back again into said enclosure by way of the ingress opening 84 intermediate the baffle 27 and adjacent convergent panel 11. The succeeding movement imparted to the disc or spider 36 completes transfer of the article-carrying board 35 into drying enclosure traversing location *a* by re-engagement of the hereinbefore described lower teeth 55, 56 with the guide rail 69. Incidentally it is worthy of note that the insets or cut-away parts 75, 76, in the cam sector or bumper 72 afford clearance for the teeth 55, 115 120 125 130

56, during the turning motions imparted to the outrigger arms 48, whereas the inset 77 is additionally functional in ensuring proper reengagement of said teeth with the guide rail 69, whereby the boards 35 are retained relatively stationary during transit through the enclosure 7. Particular attention is directed to the fact that the lugs or fingers 51-54 impart what we conveniently term 10 "quadri-functional" trips or movements to the outrigger arms 48, whereas the lower co-planer teeth 55, 56 solely serve to maintain said arms relatively stationary during progression through the drying enclosure 7 by 15 sliding engagement with the guide rail 69.

An exhaust outlet or outlets 85, is, or are, provided at suitable locations in the roof 13 of the drying enclosure 7 for the expulsion of excessive moisture-laden air; while closure strips 11', 11" may be attached to the panels 11, 11 and conform in outline generally, with the outer edge of the boards 35 to prevent unnecessary wastage of the drying medium.

In the form of our invention thus fully described, it will be observable that the planetary disc or spider 36 and associated guide rail 69 are mainly located within the drying enclosure 7, but there may be occasions where it is preferable that said parts 25 shall be exterior thereto. Such a contingency is provided for by the modified assemblage fragmentarily shown by Fig. V, whereon all parts corresponding with the preceding detailed description are distinguished by similar reference characters. However, it is particularly to be observed that the planetary disc or spider 36, guide rail 69, and bumper sector 72 are all located 30 below the drying enclosure bottom 14, the same being provided with an annular opening 86 through which the article-carrying board 35 is progressed in the manner hereinbefore set forth. Provision, however, is 35 made for substantial closure of the opening 86 by fitting each arm 48 with a lateral sheet material attachment 87 of appropriate configuration that fills in the interspaces between the successive boards when in drying enclosure progressing position. This 40 closure feature, it is to be understood, we lay no claim to per se, and it is only referred to for the purpose of clarifying a possible misconception easily associable with the modified form of our invention under 45 description.

Should it be deemed desirable that the 50 drying medium be circulated downwardly through the drying enclosure 7 and upwardly through the banks of heating coils 20; or vice versa, said enclosure may be provided with a perforate sub-floor or bottom 55 88—Fig. VI—(wholly or in part) whereby circulation can take place as directionally indicated by the arrows thereon. Furthermore, the closure elements 87 may be pro-

vided, as shown, or omitted without materially affecting the efficiency of this form of our invention. In all other respects, the type of machine just referred to conforms in assemblage and detail with the showing of 70 Figs. I-IV, hence corresponding reference characters are applied thereto, and further explanation dispensed with to avoid tautological repetition.

One feature and advantage noticeable as 75 consequent upon our novel design of drying machine is that one operative alone is able to attend to the "stripping" and "boarding" with ease, whereby the expense of operation is considerably reduced as compared with 80 the prevailing practice.

From the foregoing description, the advantages, simplicity and usefulness of our novel drying machine should be thoroughly understood without further explanation; 85 and, although we have described practical embodiments thereof somewhat minutely, it is to be explicitly understood that the same is not limited thereby, further than as indicated in the subjoined claims; for the obvious reason our said invention is capable of considerable structural variation and other usages, without departure from its scope or sacrificing any of the advantages 90 specifically enumerated hereinabove.

Having thus described our invention, we claim:

1. A drying machine comprising an enclosure with provision for egress and ingress of drying forms, pivotally mounted carriers for said forms, means for intermittently progressing the carriers, and quadri-functional trip mechanism operative concurrently with successive progressions to swing individual form carriers in reverse directions whereby 100 exterior presentation and re-entry of said forms relative to the enclosure is accomplished.

2. A drying machine comprising an enclosure with provision for egress and ingress of drying forms, pivotally mounted outriggers bearing said forms, means for intermittently progressing the outriggers, and quadri-functional trip mechanism operative 110 concurrently with successive progressions to horizontally swing individual outriggers with varying motions in opposite directions 115 whereby exterior presentation and re-entry of the forms relative to the enclosure is accomplished.

3. A drying machine comprising an enclosure with provision for egress and ingress of drying forms, pivotally mounted outriggers bearing said forms, means for intermittently progressing the outriggers, and quadri-functional trip means concurrently effective—by motion imparted thereto during successive progressions—to swing individual outriggers in opposite directions whereby exterior presentation and re-entry 130

of the forms relative to the enclosure is accomplished, said means comprising laterally directed teeth and opposed cooperative staggered obstructions.

4. A drying machine comprising an enclosure with provision for egress and ingress of drying forms, pivotally mounted outriggers bearing said forms, means for intermittently progressing the outriggers, and quadri-functional trip means concurrently effective—under motions imparted during successive progressions—to swing individual outriggers in reverse directions, whereby exterior presentation and progressive re-entry of the forms relative to the enclosure is accomplished, said means consisting of laterally directed teeth around the outrigger pivots, and opposed trip-and-follower obstructions for engaging said teeth.

5. A drying machine comprising an enclosure with provision for egress and ingress of drying forms, pivotally mounted arms bearing said forms, means for intermittently progressing said arms through the enclosure, and quadri-functional trip means concurrently effective—by motions imparted during successive progressions—to swing individual arms in reverse directions, whereby exterior presentation and progressive re-entry of the drying forms relative to the enclosure is accomplished, said means consisting of irregular lateral teeth integral with the arm pivots, and opposed stop-and-follower cam obstructions for engaging the teeth.

6. A drying machine comprising an enclosure with provision for egress and ingress of drying forms, pivotally mounted outrigger supports bearing said forms, means for intermittently progressing the outrigger supports around the enclosure, means associated with said supports effective to retain the same against rotation about their pivots during progression through the enclosure, and quadri-functional trip means operative concurrently with successive progressions to swing individual forms in reverse directions whereby their exterior presentation and re-entry relative to the enclosure is accomplished.

7. A drying machine comprising an enclosure with provision for egress and ingress of drying forms, pivotally mounted outriggers for said forms, means for intermittently progressing the outriggers, means associated with said outriggers effective to retain the same against rotation about their pivots during progression relative to the enclosure, said means embracing an annular guide-rail including a segmental cam sector, and lateral teeth integral with the outrigger pivots cooperative with the cam sector during successive progressions to swing individual outriggers in reverse directions,

whereby exterior presentation and progressive re-entry of the forms relative to the enclosure is accomplished.

8. A drying machine comprising an enclosure with provision for egress and ingress of drying forms, pivotally mounted arms for said forms, means for intermittently progressing the arms about the enclosure, means associated with the arm pivots effective to retain the forms relatively stationary during progress through the enclosure, said means including an interrupted annular guide-rail, a trip-and-follower cam sector spanning the guide-rail interruption, and lateral teeth integral with the arm supports cooperative therewith during successive progressions to swing individual arms in reverse directions, whereby exterior presentation and re-entry of the forms relative to the enclosure is accomplished.

9. In a drying machine including an enclosure with provision for egress and ingress of drying forms, means for progressing said forms about the enclosure comprising an intermittently rotatable carrier, a series of outrigger arms on which said forms are supported individually pivoted to the carrier, an interrupted annulus for retaining said arms relatively stationary during progression relative to the enclosure, and means operative concurrently with successive progressions to swing individual forms in reverse directions to effect exterior presentation and re-entry thereof relative to the enclosure.

10. In a drying machine including an enclosure with provision for egress and ingress of drying forms, the combination of an intermittently rotatable carrier, a series of outrigger arms individually pivoted to the carrier and on which said forms are supported, projections about the arm pivots, an interrupted annular guide-rail over which said projections slide for retaining the outrigger arms relatively stationary during progression relative to the enclosure; quadri-functional teeth about the arm pivots, a sector insert completing the guide-rail, and an opposed cam device; said sector, cam device and quadri-functional teeth being cooperative, whereby successively advancing outrigger arms are individually swung in reverse directions to effect exterior presentation and progressive re-entry of the forms relative to the enclosure.

11. In a drying machine including an enclosure with provision for egress and ingress of drying forms, means progressing the forms therethrough comprising an intermittently rotatable carrier, as series of outrigger arms—on which said forms are supported—pivoted to the carrier, an interrupted annular guide-rail functional to retain the outrigger arms relatively stationary during progression relative to the enclosure, a sector insert completing said annular guide-rail

having an upset bumper and lateral obstruction, an opposed radially stepped cam device, and projections about the outrigger arm pivots; said sector insert, cam device and projections being cooperative to swing individual outrigger arms in reverse directions to effect exterior presentation and re-entry of said forms relative to the enclosure.

12. In a drying machine including an enclosure with provision for egress and ingress of drying forms, outrigger supports for said forms, and means for intermittently progressing said supports; means for independently swinging successive supports in reverse directions to effect exterior presentation and progressive re-entry of the forms relative to the enclosure, said means consisting of a sector having an upset bumper, a lateral obstruction and spaced recessions; in combination with an opposed radially stepped cam, and cooperative irregular teeth about the form supports.

13. A drying machine comprising an enclosure with provision for egress and ingress of pivotally mounted forms, and means for intermittently progressing the forms therethrough, said enclosure being subdivided by vertical and diverging partitions to afford flanking passages, means providing an intermediate free-air inlet, and means for circulating a drying medium therethrough.

14. A drying machine comprising an enclosure with provision for egress and ingress of pivotally mounted forms, and means for intermittently progressing the forms through said enclosure, said enclosure being subdivided by vertical and opposed diverging

partitions to afford flanking passages, means providing an intermediate free-air inlet, an opposed spreader baffle in juxtaposed relation with respect to the ingress and egress openings, and means for circulating a drying medium through the enclosure and flanking passages.

15. A drying machine comprising an enclosure with provision for egress and ingress of pivotally mounted forms, means for intermittently progressing said forms through the enclosure, said enclosure being subdivided by vertical, opposed diverging, and parallel partitions to afford flanking passages, means providing an intermediate free-air inlet, an opposed spreader baffle in juxtaposed relation with respect to the ingress and egress openings, means for circulating a drying medium through the enclosure and flanking passages, and means within the flanking passages for heating the drying medium.

16. In a drying machine including an enclosure having means for circulating air, and means progressing drying forms therethrough; vertical, opposed diverging and parallel partitions in said enclosure with an intervening conduit from one wall of said enclosure defining a divided air flow, so that the forms are subjected to air approach from one side than subsequently from the other during passage around the enclosure.

In testimony whereof, we have hereunto signed our names at Philadelphia, Pennsylvania, this 16th day of April, 1924.

HARRY H. WIGGLESWORTH.
WILLIAM P. GREINER.
